VARIABLE PITCH PROPELLER

Walter W. Everts, Baltimore, Md., assignor to
Everel Propeller Corporation, Baltimore, Md.,
a corporation of Maryland

Application February 1, 1944, Serial No. 520,658

9 Claims. (Cl. 170—162)

1

My invention relates to variable pitch propellers.

An important object of the invention is to provide a propeller of the above mentioned character having the pitch of the blades increased by the action of centrifugal force upon the blades, while such pitch is decreased due to the action of the air pressure upon the blades caused by the driving rotation of the blades and aided by the suction action upon the front surface of the blades due to the camber of the blades.

A further object of the invention is to provide a propeller of the above mentioned character, wherein centrifugal force and the air pressure upon the blades, work in opposition to each other, thereby causing the pitch of the blades to be automatically increased, as the air pressure is reduced, when the elevation of the aircraft increases.

A further object of the invention is to provide a propeller of the above mentioned character so constructed that the pitch of the blades is increased beyond the maximum driving pitch, when the aeroplane is travelling with the engine dead, thus feathering the blades.

A further object of the invention is to provide means for mounting the blades upon the hub, for affording a powerful connection to limit the outward radial movement of the blades beyond the selected maximum diameter.

A further object of the invention is to provide a connection between the blades and the hub embodying interfitting rings having contact relation with the hub, and affording a strong and simple construction.

A further object of the invention is to provide an adjustable pitch propeller formed of relatively few parts, and which is of simple construction, reliable in operation, and may be manufactured cheaply.

Other objects and advantages of the invention will be apparent during the course of the following description:

In the accompanying drawings forming a part of this application, and in which like numerals are employed to designate like parts throughout the same,

Figure 1 is a side elevation of a variable pitch propeller embodying my invention.

Figure 2 is a front edge elevation of the same,

Figure 2^a is a section taken on the line 2^a—2^a of Figure 2,

Figure 3 is a longitudinal section taken on line 3—3, Figure 2,

2

Figure 4 is a horizontal section taken on line 4—4 of Figure 1,

Figure 5 is a diagrammatic view showing the parts in the position they occupy when the blades are at the power minimum position,

Figure 5^a is a transverse section through the blade showing the same at the power minimum pitch,

Figure 6 is a diagrammatic view showing the position that the parts occupy when the blades are in the power maximum pitch position,

Figure 6^a is a transverse section through the blade showing the power maximum pitch,

Figure 7 is a diagrammatic view showing the position that the parts assume when the blades are in the non-power maximum pitch or feathered position,

Figure 7^a is a transverse section through the blade showing the non-power maximum pitch,

Figure 8 is a side elevation of the propeller embodying a modified form of the invention, showing the blades in the outer radial portion,

Figure 9 is a front end elevation of the same,

Figure 10 is a radial section taken on line 10—10 of Figure 9,

Figure 11 is a vertical section taken on line 11—11 of Figure 8, the rings occupying the outer position with respect to the hub, when the blades have the maximum pitch,

Figure 12 is a similar view, showing the rings in the inner position that they have with relation to the hub when the blades have the minimum pitch,

Figure 13 is a section taken on line 13—13 of Figure 11,

Figure 14 is a diagrammatic view showing the relative position between the driving arm and blades when the blades have the maximum pitch, and

Figure 15 is a similar view showing the relative position between the driving arm and blades when the blades have the minimum pitch.

In the drawings, wherein for the purpose of illustration, are shown preferred embodiments of my invention, attention being called to Figures 1 to 7, the numeral 10 designates a hub or rotary driving member to be connected with or mounted upon the crank shaft of the engine. This hub or member may have a bore 11 to receive the end 50 of the crank shaft, which is rigidly held within the bore.

The numeral 12 designates propeller blades of any well known or preferred type, having axes 13 upon which the blades turn to vary their pitch.

55 The blades have the usual front cambered faces

14, leading edges 15 and trailing edges 16. The propeller when power driven rotates in the direction of the arrow, Figure 2. Each blade 12 has a tubular shank 17 at its inner end formed integral therewith, and this shank is rigidly mounted in a radial sleeve 18, by any suitable means. There are two radial sleeves which are diametrically oppositely arranged. The tubular shanks 17 are slidably mounted upon radial guides or supports 19, preferably formed integral with a sleeve 20, which in turn is slidably mounted upon the driving member or hub 11 to move longitudinally and turn with relation to the hub, as shown. A wear sleeve 21 is preferably arranged between the radial guide or support 19 and each tubular shank 17, to take up wear, and which may be removed, when desired. The wear sleeve 21 preferably projects radially inwardly beyond the shank 17 and the inner end of this wear sleeve is spaced from the sleeve 20, as shown at 22, and there is a space 22', at the outer end of the guide or support 19, as shown.

The numeral 23 designates a link or arm, which is provided at a point equidistantly spaced from its ends with an opening 24, for receiving the reduced end 25 of the driving member 11, carrying a nut 25 for clamping the link or arm 23 to the driving member or hub 11. The arm 23 is therefore rigidly mounted upon the driving member or hub 11 to rotate therewith and extends for equal distances, radially, upon opposite sides of the member or hub 11. The link or arm 23 is provided at its opposite ends with spherical sockets 27, to slidably receive balls 28, carried by shanks 29, which are rigidly mounted upon the sleeves 18, upon their front faces. Attention is called to the fact that the link or arm 23 is connected with the blades 12 through the medium of the sleeves 18 and associated elements, at the points or centers of the balls 28, which are spaced from and disposed in advance of the axes 13, Figure 1. Disposed at the rear of the blades 16 is a link or arm 30, having an opening 31, at a point equidistantly spaced from its ends, and this opening slidably receives the driving member or hub 11. The link or arm 30 is provided at its opposite ends with spherical sockets 32 slidably receiving balls 33 carried by shanks 34, rigidly attached to the sleeves 18. The link or arm 30 extends for equal distances upon opposite sides of the driving member or hub 11. The link or arm 30 is substantially identical with the link or arm 23. Each link 23 and 30 is formed in connected longitudinal sections. The link or arm 30 is pivotally connected with the blades 12 at the points or centers of the balls 33, which centers are spaced from and disposed rearwardly of the axes 13, Figure 1.

The operation of the first form of propeller is as follows:

When the propeller is rotated at a given speed at sea level, it is operating under the maximum air pressure due to the driving action of the propeller. The blades 12 will then have the minimum pitch. This is due to the fact that the air pressure acting upon the trailing portion of the blades 12, turns them upon their axes 13, in opposition to the action of centrifugal force which tends to bodily shift the blades radially outwardly. This turning movement of the blades upon their axes 13 to reduce the pitch is also aided by the suction action upon the front face of the blades due to the camber of the blades. When the blades are at the minimum pitch, link or arm 23 is inclined toward the leading edges 15 of the blades, and is hence angularly disposed with respect to

the axes 13 of the blades, while link or arm 30 is inclined toward the trailing edges 16 of the blades and is angularly disposed with respect to the axes 13. These links or arms 23 and 30 are inclined in opposite directions with relation to each other, and being inclined with respect to the axes 13, the sleeves 18 are therefore free to move radially and inwardly upon the guides or supports 19, until the ends of the wear sleeves 21 contact with the sleeve 20. When the aeroplane rises to a higher elevation, the air pressure acting upon the blades 12 due to their driving action, is reduced, and centrifugal force then moves the blades 12 radially outwardly. This radial outward movement of the blades 12 causes them to swing upon the walls 28, as they move outwardly, and the balls 33 turn the link or arm 30 upon the driving member or hub 11 until its longitudinal axis is in alignment with the axes 13 of the blades. The longitudinal axis of the link 30 is now in alignment with the longitudinal axis of the link 23. When the blades move radially outwardly due to the action of centrifugal force, they turn about the balls 28 so that their longitudinal axes are brought into alignment with the longitudinal axis of the link 23. The maximum pitch of the blades 12 is reached when the longitudinal axes of the links 23 and 30 and the axes 13 of the blades are all in alignment, the ball and socket joints then preventing any further radial outward movement of the blades.

When the engine goes dead, and the aircraft is still traveling, the blades being in any position between the minimum to the maximum driving pitch, the air pressure acting upon the front face of the blades will turn the blades upon their axes 13 to increase their pitch beyond the maximum driving pitch, thus causing the propeller to be feathered. When this occurs, the link 23 is angularly arranged, Figure 7, but extends in an opposite direction to that shown in Figure 5, since it extends toward the trailing edges of the blades. The link 30 is also angularly arranged in an opposite direction to that shown in Figure 5, and extends toward the leading edges of the blades.

In Figures 8 to 15 inclusive, I have shown a propeller embodying a second modification of the invention. This propeller comprises a tubular hub 35, to receive the crank shaft of the engine and to be rigidly mounted upon the crank shaft. Rigidly secured to the forward end of the tubular hub is a radial driving shaft or arm 36, held within openings 37.

The numeral 38 designates blades, preferably identical with the blades 12. The blades 38 have turning axes 39. These blades 38 have leading edges 40, trailing edges 41 and front cambered faces 42. The propeller is rotating in the direction of the arrow, Figure 9. The blades 38 turn upon their radial axes 39 to vary their pitch. The blades 38 are provided at their inner ends with shanks 43 and 44. Rigidly secured to the shank 43 is a radial shank 45, having a ring 46 rigidly secured thereto. Rigidly secured to the shank 44 is a radial shank 47, having a ring 48 rigidly secured thereto. The rings 46 and 48 interfit, each ring extending through the other, adjacent to the radial shank. At the radial shank 45, ring 46 has a radial pin 49 pivotally mounted in a radial recess 50, formed in the ring 48. At the shank 47 the ring 48 has a radial pin 51, pivotally mounted in a radial recess 52, formed in the ring 46. The rings 46 and 48 are adapted to turn upon the radial pins 49 and 51,

and these radial pins are in alignment with the axes 39. The tubular hub 35 extends through the rings 46 and 48, and contacts with the portions of these rings remote from the radial shanks 45 and 47.

Arms 52 extend forwardly and generally axially of the tubular hub 35 and are rigidly secured to the radial shanks 45 and 47. These arms have at their forward ends, ball and socket connections 53, with sleeves 54, which are slidably mounted upon the radial driving shaft or arm 36, to turn thereon and move longitudinally thereof.

The operation of the propeller is as follows:

The propeller is driven counter-clockwise, Figure 9, and the air pressure acting upon the rear faces of the blades 38, and the action of the camber at the front faces of the blades, turn the blades 38 upon their axes 39 to reduce the pitch of the blades. At sea level, the blades would have the minimum pitch and the shortest radius. The radial driving shaft or arm 36 is now inclined with respect to the axes 39 of blades. This is indicated diagrammatically in Figure 15. When the blades turn upon their axes to the minimum pitch, the curved ends of the rings 46 and 48 remote from their shanks, ride upon the curved surfaces of the cylindrical hub 35, whereby the rings have their shanks 45 and 47 drawn radially inwardly, thereby shortening the radius of the blades 38, Figure 11. When the aircraft rises to a higher elevation, the air pressure upon the blades is reduced, and the action of centrifugal force upon the blades moves them radially outwardly. In order that this radial outward movement may be produced, the blades turn upon their axes 39 to increase their pitch, the ends of the rings 46 and 48 turning about the curved face of the tubular hub 35 whereby the shanks 45 and 47 move radially outwardly, Figure 12. When the maximum pitch of the blades is obtained, the shaft or arm 36 is in alignment with the axes 39 of blades Figures 8, 9, and 14. When the shanks 45 and 47 move radially inwardly and the pitch of the blades is reduced, the rings 46 and 48 contact at A, and are spaced from the hub 35 at B. When the shanks 45 and 47 move radially outwardly and the pitch of the blades is increased, the rings 46 and 48 are spaced at A and contact with the hub 35 at B.

The radial driving shaft or arm 36 serves to impart rotation from the hub 35 to the blades and to also hold the blades against improper axial movement upon the hub. The rings 46 and 48 having their ends slidably engaging the curved face of the hub 35, effect the inward radial movement of the blades, when their pitch is decreased, and increase the pitch of the blades when they are moved radially outwardly by centrifugal force. The rings 46 and 48 contact with the hub 35 to form a powerful connection to hold the blades against radial movement in an outward direction beyond the selected maximum diameter.

While the propellers are designed primarily for use on aircraft, they may be used for other purposes, such as upon boats, or upon windmills.

It is to be understood that the forms of my invention herewith shown and described are to be taken as preferred examples of the same, and that various changes in the shape, size, and arrangement of parts, may be resorted to, without departing from the spirit of my invention or the scope of the subjoined claims.

Having thus described my invention, I claim:

1. In an automatic variable pitch propeller, a

rotary driving member, propeller blades having turning axes, means to mount the blades upon the driving member to simultaneously move radially and turn upon their axes with relation thereto and to move axially of the driving member, said means having a camming action with the member to draw the blades radially inwardly when they are turned upon their axes to reduce their pitch, and a driving element separate from the mounting means and mounted upon the driving member and connected with the blades so that the driving member rotates the blades.

2. In an automatic variable pitch propeller, a hub, propeller blades having turning axes, rings rigidly secured to the inner ends of the blades, said rings interfitting and mounted upon the hub to slidably engage thereon, arms connected with the rings and extending axially of the hub, a driving arm mounted upon the hub, sleeves slidably mounted upon the driving arm, and universal connections between the sleeves and the arms secured to the rings.

3. In an automatic variable pitch propeller, a hub, propeller blades having turning axes, interfitting rings mounted upon the hub, radial shanks carried by the rings and secured to the blades and in alignment with the axes of the blades, a pin for pivotally connecting the end of each ring remote from its shank with the other ring adjacent to the shank of the other ring, the pin being in alignment with the axis of the blade, a driving arm carried by the hub, and devices connecting the driving arm with the shanks of the rings.

4. An automatic variable pitch propeller, comprising a rotary driving member, propeller blades, means to mount the propeller blades upon the driving member to simultaneously move radially and turn upon their axes with relation to the driving member while the driving member is rotating, the outward radial movement of the blades being due solely to the action of centrifugal force and the turning movement of the blades upon their axes to reduce their pitch being due solely to the action of air pressure upon the blades, said means including loops receiving the driving member therein, said loops interfitting with each other and having cam portions providing a cam action with the rotary member to draw the blades radially inwardly when they are turned upon their axes to reduce their pitch, the cam portions having a camming action with the rotary member to turn the blades upon their axes in an opposite direction to increase their pitch when the blades are moved radially outwardly by centrifugal force, and driving connecting means between the rotary member and the blades.

5. An automatic variable pitch propeller, comprising a rotary driving member, propeller blades, means to mount the propeller blades upon the driving member to simultaneously move radially and turn upon their axes with relation to the driving member while the driving member is rotating, the outward radial movement of the blades being due solely to the action of centrifugal force and the turning movement of the blades upon their axes to reduce their pitch being due solely to the action of air pressure upon the blades, said means including substantially flat loops receiving the rotary driving member and extending generally transversely of the driving member, said loops interfitting so that the end of each loop remote from its blade engages the rotary member while its opposite end is held out of engagement with the driving member, the ends of the loops engaging the driving member having cam por-

tions providing a cam action with the rotary member to draw the blades radially inwardly when they are turned upon their axes to reduce their pitch, the cam portions providing a camming action with the rotary member to turn the blades upon their axes in an opposite direction to increase their pitch when the blades are moved radially outwardly by centrifugal force, and driving connecting means between the rotary member and the blades.

6. In a propeller, a rotary driving member, propeller blades arranged near the driving member and having turning axes arranged permanently radially of the driving member, loops attached to the inner ends of the blades and receiving the driving member through them, said loops interfitting with each other and having turning axes extending radially of the driving member and in alignment with the radial turning axes of the blades, each loop having an inclined part arranged remote from the blade of the loop, said inclined part having a camming action with the driving member when such blade is turned upon its axis to reduce the pitch of the blade, driving means mounted upon the driving member to rotate therewith, and a device connected with each blade and extending generally axially of the rotary driving member and connected with the driving means.

7. In an automatic variable pitch propeller, a substantially cylindrical hub, propeller blades arranged near the hub and having variable pitch turning axes arranged radially of the hub, rings secured to the inner ends of the blades and receiving the hub therein, said rings interfitting with each other and having turning axes disposed radially of the hub and in alignment with the turning axes of the blades, each ring having its part remote from the blade of the ring engaging with the hub for producing a camming action which draws such blade radially inwardly when the blade is turned upon its axis to reduce its pitch, a driving member mounted upon the hub to rotate therewith, and means connecting the blades with the driving member, such means swinging with the blades when they turn on their axes.

8. In an automatic variable pitch propeller, a rotary driving member, blades arranged near the member and having variable pitch turning axes arranged substantially radially of the member, loops connected with the inner ends of the blades and receiving the rotary member therein, said

loops interfitting with each other and having turning axes substantially radial of the driving member and in substantial alignment with the axes of the blades, said loops slideably engaging the driving member to turn thereon and move axially thereof, a driving device mounted upon the driving member to rotate therewith and held against axial movement with relation to the driving member, and elements extending generally axially of the driving member and attached to the blades and connected with the driving device.

9. In an automatic variable pitch propeller, a driving member, propeller blades arranged near the driving member and having variable pitch turning axes arranged substantially radially of the driving member, loops attached to the inner ends of the blades and receiving the driving member therein, a pin for pivotally connecting the end of each loop remote from its blade with the other loop, the pin causing the loops to turn upon an axis substantially radially of the driving member, the loops being slideably mounted upon the driving member, each loop having a camming action with the driving member at a point remote from the blade of such loop to draw such blade radially inwardly when the blade turns upon its axis to reduce its pitch, a driving device mounted upon the driving member, and means connecting the driving device and blades.
